UNITED STATES PATENT OFFICE.

PETER HALL, OF PASADENA, CALIFORNIA.

HINGE.

1,318,663.

Specification of Letters Patent.

Patented Oct. 14, 1919.

Application filed April 19, 1919. Serial No. 291378.

To all whom it may concern:

Be it known that I, PETER HALL, a citizen of the United States, residing at Pasadena, in the county of Los Angeles and State 5 of California, have invented a new and useful Hinge, of which the following is a specification.

My invention relates to an improved form of hinge, being more particularly a hinge 10 applicable for use upon boxes of light construction such as wooden boxes used for packing candy and other similar articles.

The principal object of my invention is to produce a hinge of the class described, of 15 simple form and construction, which may be used upon boxes of very light wood construction.

Other objects and advantages will appear hereinafter from the following description.

20 Referring to the drawings, which are for illustrative purposes only,

Figure 1 is a perspective view of a box with hinges thereon embodying a form of my invention.

25 Fig. 2 is a view of a portion of the box showing the lid in open position.

Fig. 3 is an enlarged perspective view of the face of the hinge.

30 Fig. 4 is an enlarged perspective view of the hinge showing the back of same.

Fig. 5 is an enlarged vertical sectional view showing a portion of the top and one side of the box and the hinge in position thereon.

35 Fig. 6 is an enlarged perspective view of a hinge embodying a modified form of my invention.

Fig. 7 is an enlarged vertical sectional view of a portion of the top and one side of 40 the box, showing mounted thereon a hinge embodying the form shown in Fig. 6.

The box shown is a wooden box having a top or lid 11, a bottom 12, sides 13, a front 14 and back 15. 16 designates the hinge 45 consisting of a flat plate, there being one hinge at each side of the box at the rear end thereof. The hinge is, in the form shown, substantially triangular in shape having a hole or perforation 17 therein near its lower end which receives a small brad or nail 18, such nail extending into the edge of the back as shown in Figs. 1 and 2. The nail 18 forms the pivot for the hinge, being driven into the box sufficiently tight to hold 55 the top or cover in proper alinement with

the box, but at the same time permitting a free movement of the hinge against the sides of the box.

The upper portion of the plate forming the hinge is turned inwardly forming a 60 flange 19 which extends over and engages the lid of the box. Punched out of the plate 16 are ears 20 which extend inwardly parallel to the flange 19, the ears 20 engaging the under side of the top, and together with the flange 19, forming a clamp over that portion of the edge of the top 11 between the flange and the ears.

The plate 16 is provided with perforations or openings 21 through which brads or nails 70 22 are driven into the edge of the top, securely fastening the lid or top to the hinge.

In the form shown in Figs. 6 and 7 the hinge plate 25 is provided with an inwardly turned flange 26 at the top thereof, such 75 flange, however, being provided with spurs 27 which are pressed into the lid. The hinge plate 25 is also provided with ears 28 punched therefrom and which extend inwardly under the lid of the box, such ears 80 having spurs 29 formed thereon which press into the under side of the lid whereby the lid is firmly clamped and held to the hinge plate without the necessity of using nails in the hinge for engaging the lid of the box. 85 The hinge plate 25, however, is provided with a perforation 30 for receiving a nail or brad 31 which extends into the back of the box to form a pivot for the hinge.

By using the form of hinge shown I am 90 enabled to use much thinner material for the box than can ordinarily be done where no clamping device is formed on the hinge for engaging the edge of the lid, and by using the hinge shown and described I am 95 able to more economically make a box of cheaper construction than can be done with the common form of hinges now in use.

In using the form of hinge shown in Figs. 1 to 5 inclusive, the operation of assembling 100 the lid and box is greatly facilitated as this operation is performed by hand and the flanged ears on the hinge engaging the lid assist in holding the lid in proper relation with the box during the nailing operation, a 105 further advantage being that the material of the lid being clamped between the flange and ears, a much thinner lid may be employed without the danger of splitting caused by driving the brads or nails into the 110

edge of the lid when the clamping flange and ears are not used.

While I have particularly described my invention as used upon wooden boxes it is 5 to be understood that the hinge may be used upon boxes made of other material without departing from the spirit of my invention.

What I claim is:—

A hinge for box lids comprising a plate 10 arranged to swing edgewise, means for pivotally mounting the lower end of the plate

to the body of the box, a flange formed on the upper end of the plate extending inwardly therefrom in engagement with the upper face of the lid of the box, and ears 15 formed on said plate extending inwardly therefrom in engagement with the lower face of said lid.

In testimony whereof, I have hereunto set my hand at Los Angeles, California, this 3rd 20 day of April, 1919.

PETER HALL.
